[57] CLAIM

The ornamental design for combined dolls and carrier, as shown and described.

DESCRIPTION

FIG. 1 is a front elevation view of combined dolls and carrier showing my new design;

FIG. 2 is a rear elevation view of the design;
FIG. 3 is a right side elevation view thereof, the left side elevation view being substantially the same;

FIG. 4 is a top plan view of the design; and
FIG. 5 is a bottom plan view of the design.
